UNITED STATES PATENT OFFICE

2,357,007

CLOSURE FASTENER

Richard B. Jones, Rapid City, S. Dak.

Application April 7, 1943, Serial No. 482,160

3 Claims. (Cl. 292—335)

This invention relates to new and useful improvements in closure fasteners such as may be used for doors on refrigerators, aeroplanes, automobiles and sundry other instances.

The principal object of the present invention is to provide a closure fastener which will be self-latching and in acting in this respect will serve to snugly hold a closure against any looseness that would tend to permit the escape of air, especially in instances where a door is constructed for air tightness.

Another important object of the invention is to provide a closure fastener of the character stated which will be positive acting and substantially foolproof at all times.

Other objects and advantages of the invention will become apparent to the reader of the following description.

In the drawings:

Figure 1 represents an outside fragmentary elevational view showing in broken lines the position of the fastener and in full lines the operating member therefor.

Figure 2 is a fragmentary sectional view taken on the line 2—2 of Figure 1, but showing the fastener in closed position.

Figure 3 is a fragmentary sectional view taken substantially on the same line as Figure 2, but showing the fastener in open position.

Figure 4 is a fragmentary detailed sectional view similar to that of Figures 2 and 3 but showing the closure with the fastener being moved to open position.

Figure 5 is a vertical sectional view through the fastener.

Figure 6 is a horizontal fragmentary sectional view taken substantially on the line 6—6 of Figure 1.

Figure 7 is a fragmentary elevational view of the keeper.

Referring to the drawings wherein like numerals designate like parts, it can be seen that numeral 5 denotes a closure while numeral 6 represents some stationary structure such as a wall or the like.

Numeral 7 generally refers to the closure fastener which includes a box 8 horizontally through which a bolt 9 of polygonal cross section is slidably disposed. On the bolt 9 is a collar 10 from which depends a finger 11 and located on the bolt 9 is a coiled compression spring 12 which is interposed between one side wall of the box 8 and the collar 10. The spring 12 serves to urge the bolt to operated position as shown in Figure 2.

Numeral 13 denotes a shaft which extends

through the closure 5 and is operated by a handle 14. The shaft 13 at a point within the box 8 carries a plate 15 which has a shoulder portion 16 adapted to abut the finger 11. A spring 17 convoluted on the shaft 13 and having one end bearing against the box 8 and the other against the shoulder 16 serves to maintain the shaft 13 and the handle 14 in substantially the position shown in Figures 1 and 2. A stop 18 is provided in the box 8 for the plate 15.

The bolt 9 slides through a bracket structure 19 vertically through which is disposed a shaft 20 having a crank 21 at its upper end, this crank being engageable against a strip spring 22 suitably secured to the back wall of the box 8. An L-shaped detent 23 is carried by the shaft 20 and has a lug 24 at one end thereof engaged with a recess 25 of the bolt 9. The other end of the rockable detent is engageable by the head of a pin 26 which is slidably disposed through a guide 27 at one side of the box 8.

A channeled flapper 28 receives one end of the bolt 9 and is pivotally secured thereto as at 29. The pin 26 extends into the flaper 28 and engages the same as substantially shown in Figure 3.

An inclined keeper 30 having a roller 31 at its low point serves as a wedge against which the flapper 28 can act in wedging the closure 5 to a snug closed position.

It can be seen that when the handle 14 is pushed downwardly, the shoulder 16 will act against the finger 11 and force the bolt 9 to the right in Figures 2 and 5, to the position substantially shown in Figure 3, until such time as the recess 25 reaches the lug 24 of the detent 23 whereupon the spring 22 will act on the crank 21 and move the lug 24 into the recess. The door 5 can now be pulled open and the handle 14 released. The parts will remain in the position shown in Figure 4.

When the door 5 is closed, the flapper 28 will ride against the roller 31, forcing the pin 26 inwardly and rocking the detent 23, so that just as the flapper substantially passes the roller 31, the lug 24 will be removed from the recess 25, thus freeing the bolt 9 so that the spring 12 throws the bolt and flapper 28 to the left as shown in Figure 2.

50 The flapper 28 will ride the slope of the keeper 30 and this wedging action will draw the door 5 snugly against the jamb.

While the foregoing specification sets forth the invention in specific terms, it is to be understood that numerous changes in the shape, size and

materials may be resorted to without departing from the spirit and scope of the invention as claimed hereinafter.

Having described the invention, what is claimed as new is:

1. A closure fastener comprising a stationary keeper having an inclined portion, a movable closure, a spring projected bolt on the closure, manual means for retracting the bolt, said bolt being provided with a pivotal rider at one end thereof for riding the slope of the keeper, and detent means for the bolt, said detent means comprising a rockable member adapted to hold the bolt in retracted position, and a slide pin operated by the rider at its retracted position for tripping the detent member. 10

2. A closure fastener comprising a stationary keeper having an inclined portion, a movable closure, a spring projected bolt on the closure, manual means for retracting the bolt, said bolt being provided with a pivotal rider at one end 20

thereof for riding the slope of the keeper, and detent means for the bolt, said detent means comprising a rockable member adapted to hold the bolt in retracted position, and a slide pin 5 operated by the rider at its retracted position for tripping the detent member, said detent member being provided with a crank and a spring acting on the crank to move the detent to holding position with respect to the bolt.

3. A closure fastener comprising a stationary keeper having an inclined portion, a movable closure, a bolt on the closure having projecting and retracting means, said bolt being provided with a pivotal rider at one end thereof for riding the slope of the keeper, detent means for the bolt, said detent means comprising a rockable member adapted to hold the bolt in one position, and a slide pin operated by the rider for tripping the detent member. 15

RICHARD B. JONES.
